UNITED STATES PATENT OFFICE.

ALVIN M. ROSENBERRY, OF SHELBY, OHIO, ASSIGNOR OF ONE-HALF TO
MACK H. DAVIS, OF SHELBY, OHIO.

CARBURETER.

SPECIFICATION forming part of Letters Patent No. 709,647, dated September 23, 1902.

Application filed December 2, 1901. Serial No. 84,404. (No model.)

To all whom it may concern:

Be it known that I, ALVIN M. ROSENBERRY, a citizen of the United States, residing at Shelby, in the county of Richland and State 5 of Ohio, have invented certain new and useful Improvements in Apparatus for Manufacturing Air-Gas, of which the following is a specification.

My present invention pertains to improvements in apparatus for carbureting air or manufacturing "air-gas," the construction and advantages of which will be hereinafter set forth, reference being had to the annexed drawings, wherein—

15 Figure 1 is a side elevation, partly in section, of my improved plant or apparatus; Fig. 2, a sectional view of the regulator; Fig. 3, a transverse sectional view on the line 2 2 of Fig. 2, and Fig. 4 a side elevation showing 20 in detail a portion of the device.

One object of my invention is to furnish an apparatus wherein air-gas of a given or fixed quality may be produced in the exact quantity required from time to time.

25 A further object of the invention is to provide an apparatus wherein the gas will be manufactured only as required and the quantity of air passed through the carbureter will be proportionate to the feed of the hydrocarbon and to the consumption of the air-gas.

In the apparatus about to be described hydrocarbons of varying specific gravity may be employed at one and the same time, the device separating the different grades and 35 bringing each into contact with a current of air in succession, the heaviest grades being first exposed to the air and the lightest last exposed.

With the above objects or ends in view I 40 have constructed an apparatus upon the lines of the accompanying drawings and herein-after described in detail.

Referring to the drawings, A designates an air reservoir or receiver to which air under 45 pressure is supplied by a pipe B from any suitable source. A pipe C extends from the air-space within the reservoir to the lower part of a cylindrical chamber or cylinder D. This cylinder is in communication with a sec- 50 ond and smaller cylinder E, the communication being effected through an opening F,

formed in the intervening wall between the cylinders. Within the cylinder D there is mounted a piston G, said piston being formed with a rib or projection H upon one side there- 55 of, the rib extending into the slot or passage-way F, thereby serving to prevent rotation of the piston within the cylinder. In other words, the rib acts as a guide for the piston.

The piston-rod I, which is connected to the 60 piston G, extends up through a suitable stuffing-box and in turn is connected to a bell-crank lever J, which is fulcrumed at K to an arm or bracket L, which is rigidly fixed to any suitable support. In the present in- 65 stance it is shown as connected to one of the pipes, which will be hereinafter referred to.

The outer end of the elbow-lever J is connected to the valve-stem of a needle-valve M, which works in a pipe N, said pipe affording 70 communication between the hydrocarbon or gasolene tank O and the upper end of the carbureting-chamber P.

From the description thus far given it will be seen that as the piston G is moved up or 75 down the valve M will be opened or closed, permitting or shutting off the flow of the gasolene or other hydrocarbon from the gasolene tank or reservoir to the carbureting apparatus proper.

To properly regulate the amount of air 80 which passes from the cylinder D through cylinder E, thence through pipe Q to the bottom of the carbureting-chamber, there is mounted within the cylinder E a cylindrical 85 valve R, open at its lower end and provided with a slot or opening S in its side wall of a length and width equal to the passage F. The valve R is provided with a stem which extends outwardly through the head of the 90 cylinder, the stem being squared, so that the valve may be turned to vary the position of the slot or opening S with reference to the slot or passage-way F, thereby increasing or diminishing the size of the passage from the 95 one cylinder to the other as may be desired. The amount of opening is also regulated by the movement of the piston G. In the position shown in full lines in Figs. 1 and 2 the piston is in its lowermost position and the 100 passage of air prevented. It will also be noted upon reference to Fig. 1 that when the

piston G is in its lowermost position the valve which controls the gasolene-supply is likewise closed. As the piston rises the valve is opened proportionately, so that the feed of 5 gasolene is regulated according to the volume of air which passes through the carbureter. The elevation of the piston and the consequent opening of the valve are dependent upon the amount of gas or air-gas which is 10 being withdrawn from the carbureter. For instance, if but a small quantity is being used and but a small quantity being withdrawn from the carbureter the air-supply will be in proportion to the amount of air-gas being 15 consumed. Likewise the feed of the gasolene will be in direct proportion to the volume of air passing through the carbureter. When the consumption is stopped, the pressure in the carbureter and the air-tank becomes equalized and the piston G drops to the bottom of 20 the cylinder, shutting off any further air-supply and at the same time shutting off the feed of the gasolene or other hydrocarbon.

The carbureter which I have employed 25 consists, essentially, of a cylindrical jacket or vessel, in which is mounted a series of pans or disks a, inclining toward a central perforation b, formed therein. Mounted upon each of said pans is a frusto-conical member or 30 deflector c, legs d being employed to elevate the deflector to a slight extent from the pans or disks.

As will be noted upon reference to Figs. 1 and 4, the under side of each pan and each 35 deflector is inclined, so that the pans and the said under sides or faces are parallel throughout. In this manner the air or air-gas which may be passed between the two will be distributed equally all around the deflector and 40 pass up on all sides thereof.

Mounted upon the pan and over the deflector and at a slight distance therefrom is a foraminous body T, preferably formed of wire-gauze or the like. Said body takes the general form of the deflector; but instead of having a perfectly plain surface it is formed with a spiral groove or channel which extends entirely around the same from the upper to the lower edge thereof.

50 The gasolene-feed pipe discharges directly over the uppermost foraminous body and passes down around and through the same, coming in close and intimate contact with the air which is passed in through the pipe Q at the lower end of the carbureting-chamber. Should the gasolene or other hydrocarbon which is being used be of different or varying specific gravities, the heavier grades will find their way quickly to the lower end of the carbureting-chamber or to the lowermost of the foraminous bodies. At this point it will come into direct contact with the air which has not been charged with the hydrocarbon vapors. As a consequence the heavier grades will be 65 taken up by this fresh air, and the lighter grades, which naturally remain in the upper portion of the carbureter, will be taken up by

the partly-charged air, and a complete and stable air-gas will be formed.

By the formation of the spiral groove or 70 channel in the foraminous body the gasolene is prevented from running directly to the bottom of the foraminous body. It is found that it will run around or follow the line of the groove, channel, or depression and finally, if 75 there be any unevaporated, find its way to the disk or pan a and through the opening therein to the uppermost portion of the foraminous body immediately below. The air must of course take a circuitous or zigzag course of 80 travel from the bottom of the carbureter to the top thereof, passing through and about each of the foraminous bodies before it can reach the outlet e. To said outlet there is connected a pipe f, which leads to the point of 85 consumption of the gas, and a second pipe g, which extends upwardly and opens into the upper portion of the gasolene-tank O. Pipe g serves to equalize the pressure in the apparatus, preventing the gasolene from being 90 forced out of the tank, as well as preventing the exertion of any back pressure therein by the air coming in from the carbureting-chamber.

From the foregoing description it will be 95 seen that the operation of the apparatus is automatic throughout and that immediately the consumption is stopped the feed of gasolene to the carbureter and the air-supply is automatically cutoff. So, too, the amount of 100 air which passes through the regulating apparatus to the carbureter and the amount of gasolene which is fed into the carbureter are directly proportionate to each other and to the consumption. By turning or adjusting valve 105 R the quantity of air which may pass through the openings G and S may be determined and regulated according to the grade of gasolene or other hydrocarbon being used. It is also to be noted that no heating device is employed 110 in connection with this apparatus, it being simply necessary in order to insure the proper operation thereof to store up sufficient air in the tank or reservoir A. Otherwise the apparatus is automatic throughout. There is 115 no quantity of gas stored at any point, except that slight amount which may be present in the carbureting-chamber.

The piston G may be termed a "motor"—that is to say, it is actuated or moved by the 120 air passing to the carbureter when the pipe f is open and in so moving opens the air-supply between the reservoir A and the carbureting-chamber, at the same time actuating and regulating the gasolene-supply valve.

Should the air contain moisture, means 125 must be provided for withdrawing it from the lower portion of the carbureting-chamber. The water will of course settle to the bottom, and to dispose of it a float-valve i is provided, the valve proper, j, opening through the lower portion of the carbureting-chamber and permitting the water to escape when it reaches a predetermined level. Should excess of hy-

drocarbon be admitted to the carbureting-chamber, it will also escape through said valve.

Having thus described my invention, what I claim is—

- 5 1. In combination with a carbureting-chamber; a normally closed hydrocarbon - feed leading to said chamber; a suitable air-supply also communicating with the chamber; a valve for opening and closing the hydrocarbon-feed; and means connected to said valve and operated by the air passing to the carbureting-chamber from the air-supply, said means opening and closing the valve in proportion to the amount of air-gas withdrawn 15 from the carbureting-chamber.
2. In combination with a carbureting-chamber; a normally closed hydrocarbon - feed leading to said chamber; a suitable air-supply also communicating with the chamber; a valve for opening and closing the hydrocarbon-feed; and a motor located in the air-supply pipe and connected to the valve, said motor serving to regulate the quantity of air passing to the carbureting-chamber and to 25 open and close the gasolene-feed valve in proportion to the amount of air-gas withdrawn from the carbureting-chamber.
3. In combination with a carbureting-chamber; a normally closed hydrocarbon - feed 30 leading to said chamber; a suitable air-supply also communicating with the chamber; a valve for opening and closing the hydrocarbon-feed; a motor located in the air-supply pipe and connected to the valve, said motor 35 serving to regulate the quantity of air passing to the carbureting-chamber and to open and close the hydrocarbon-feed valve in proportion to the amount of air-gas withdrawn from the carbureting-chamber; and means 40 for regulating the action of the motor.
4. In combination with a carbureting-chamber; a hydrocarbon-feed leading to said chamber; a source of air-supply; a pipe connecting said source of supply and the carbureting-chamber; a cylinder located in said pipe; a piston mounted within said cylinder and serving to open and close the passage in the pipe in proportion to the amount of air-gas withdrawn from the carbureting-chamber; a valve 45 for opening and closing the hydrocarbon-feed; and connections intermediate said valve and the piston, whereby the valve will be operated in consonance with the movements of the piston.
5. In combination with a carbureting-chamber; a hydrocarbon-feed leading to said chamber; a source of air-supply; a pipe connecting said source of supply and the carbureting-chamber; a cylinder located in said pipe; a piston mounted within said cylinder and serving to open and close the passage in the pipe in proportion to the amount of air-gas withdrawn from the carbureting-chamber; a valve for opening and closing the hydrocarbon-feed; and connections intermediate said valve and the piston, whereby the valve will be operated in consonance with the movements of the piston.
6. In combination with a carbureting-chamber; a source of air-supply; a pipe leading from said source of air-supply; a cylinder connected to said pipe; a piston mounted in said cylinder; a valve-chamber communicating with said cylinder; a regulating-valve located in said chamber; a pipe leading from said chamber to the carbureting-chamber; a valve located in the hydrocarbon-feed; and connections intermediate said valve and the piston - rod, whereby the piston and valve work in unison.
7. In combination with a carbureting-chamber; a hydrocarbon-feed leading to said chamber; a suitable air-supply also communicating with said chamber; a valve for opening and closing the hydrocarbon - feed; means connected to said valve and operated by the air passing to the carbureting-chamber from the air-supply, said means opening and closing the valve in proportion to the amount of air-gas withdrawn from the carbureting-chamber; a series of dished disks or pans mounted in said carbureting-chamber, each provided with a central opening; a cone-shaped deflector mounted on said pans at a slight distance above the same; and a foraminous cone-shaped member also mounted on the pans and standing at a slight distance from the deflector.
8. In combination with a carbureting-chamber; means for supplying gasolene to the upper end thereof; means for supplying air to the lower end thereof; a series of dished disks or plates mounted in said chamber, each plate being provided with a central opening or aperture; a cone-shaped deflector mounted on each of said disks and at a slight distance therefrom; and a foraminous body seated on each of said disks and surrounding the deflectors at a slight distance therefrom, said bodies being formed with a spiral channel or depression which extends from the upper to the lower end thereof.
9. An evaporating - surface for hydrocarbon - vaporizers, comprising a foraminous body having a generally cone-shaped contour, with a spiral channel or depression extending around the same from the upper end to the lower edge thereof.
10. In testimony whereof I have signed my name to this specification in the presence of two subscribing witnesses.
